UNITED STATES PATENT OFFICE.

EDWARD F. MONTGOMERY AND REUBEN B. BURNHAM, OF BURKEVILLE, TEXAS, ASSIGNEES, BY DIRECT AND MESNE ASSIGNMENTS, OF SEVENTY ONE-HUNDREDTHS TO SAID BURNHAM AND FIFTEEN ONE-HUNDREDTHS TO J. F. WESTBROOK, OF BURKEVILLE, TEXAS, AND FIFTEEN ONE-HUNDREDTHS TO S. H. WESTBROOK, OF FARRELLVILLE, TEXAS.

POWER-TRANSMITTING DEVICE.

1,254,617.

Specification of Letters Patent. Patented Jan. 22, 1918.

Application filed May 9, 1916. Serial No. 96,432.

To all whom it may concern:

Be it known that we, EDWARD F. MONTGOMERY and REUBEN B. BURNHAM, citizens of the United States, residing at Burkeville, in the county of Newton and State of Texas, have invented new and useful Improvements in Power-Transmitting Devices, of which the following is a specification.

This invention relates to a power transmitting device, its object being to provide a device by means of which power taken from any suitable source may be economically transmitted and multiplied, for the purpose of driving machinery or other purposes.

A further object of the invention is to provide a power transmitting device composed of primarily driven cam wheels operating through a system of vibrating levers for transmitting rotary motion to a driven shaft from which the applied power is to be transmitted, the sets of levers actuated by the respective cams operating alternately and intermittently through ratchet mechanism to turn the driven shaft and thereby impart continuous driving motion thereto.

The invention consists of the features of construction, combination and arrangement of parts herein fully described and claimed, reference being had to the accompanying drawings in which:

Figure 1 is a side elevation of a power transmitting device embodying our invention.

Fig. 2 is a top plan view of the same.

Fig. 3 is an opposite side elevation.

Fig. 4 is a front elevation.

Figs. 5 and 6 are vertical transverse sections on the lines 5-5 and 6-6 of Fig. 1.

Referring to the drawings, 1 designates a suitable base or foundation, from which rise pairs of bearing or supporting standards 2, 3 and 4. Journaled upon the standards 2 is a driving shaft 5, one end 6 of which is provided with a crank 5' or other means for applying power thereto from a suitable source, such as a water wheel, wave power apparatus, or any other primary source of power.

The shaft 5 carries a pair of cam wheels or disks 6 and 7, which may be united for operation as a unit, and the outer faces of these respective cam wheels or disks are pro-

vided with cam grooves 6' and 7', which are preferably of square or rectangular formation as shown, thus providing angular points or projections 8, for a purpose herein-after described. The grooves and cam points of the two wheels or disks are arranged at an angle to each other and at different angles to the shaft or their center of rotation, the corresponding points of the cams being arranged at angles of 90° to each other, as shown.

Arranged on each side of the double cam wheel or disk is a set or series of motion transmitting levers, each comprising a primary lever 9 having at one end a friction roller 10 to travel in the adjacent cam groove, said lever being fulcrumed between its center and opposite end upon a rod 11, the ends of said rod being supported by the standards 3. The rollers 10 are thus carried by the long arms of the levers 9, and the short arms of said levers are connected by links 12 with the short arms of secondary levers 13.

The levers 13 are fulcrumed upon a rod or shaft 14 supported by the standards 3, and each lever 13 has its arm provided with a weight 15, which may be adjustably mounted thereon, and which is designed to approximately balance the weight of the long arm of the associated lever 9, whereby through the balancing action obtained ease of working motion is secured. The long arm of each lever 13 is connected by a link 16 with one, the long, arm of a tertiary or final lever 17, which is fulcrumed between its center and one end upon a transverse rod or shaft 18 supported by an upright 19, said upright having guide slots to receive the pivoted ends of the levers 17, which are thus guided in motion and limited in lateral play from looseness due to wear or other causes.

The short arms of the lever 17 have pivotally connected therewith, as at 20, rack bars 21 and 21' which have lower toothed ends or faces 22, which mesh with ratchet wheels 23 and 23' on a transverse driven shaft 24 journaled in suitable bearings on the uprights 4, and from which shaft motion may be transmitted through a pulley 25 or other means to the device, machine or apparatus to be driven. The ratchet wheels 23 have their teeth facing in the same direc-

tion, and in the action of each rack bar said bar is adapted to slide upward, on its inactive motion, over the curved faces of the ratchet teeth and on its downward motion to engage the teeth and impart motion to the ratchet wheel, a spring 26 or other elastic connection being provided between the upper end of each rack bar and a stationary part of the frame to normally hold the toothed end of said rack bar in engagement with the ratchet wheel and permit the same to recede or have riding motion on the ratchet teeth on the inactive motion of said rack bar.

In the operation of the device, it will be understood that the drive shaft 5 is primarily driven from any suitable source of power and transfers motion to the double cam wheel, by which rocking motions will be imparted throughout to the sets of levers the levers of each set being moved alternately and in opposite directions in unison so that when one rack bar is on its working stroke the other will be on its return stroke, and vice versa, thus imparting an intermittent motion to the driven shaft through the medium of each set of power devices, which is converted into continuous motion by the alternate power transmitting action of the two sets of power devices, it being evident that the rocking motion imparted to the two sets of levers is obtained from the cam points 8 of the two cam grooves which are arranged on lines intermediate each other and at such angular relationship as to secure the working action described.

It will be evident that through the mode of pivoting the several levers of each set, the power applied to the primary lever will be multiplied to a considerable degree, and the power obtained may be varied by varying the fulcrum points of the levers as desired. It will also be evident that by the use of the weights 15 the levers 9 and 13 are balanced in action while said weights operate to hold the long arms of the levers 9 upward and thus maintain the friction rollers 10 thereon in engagement with the inner walls of the cam grooves provided with the points 8, whereby a positive and reliable working motion is obtained.

I claim:—

In a device of the class described, the combination with a driving wheel having cams in its opposite faces; of a series of multiplying levers pivoted between their ends, rollers on the long arms of the first levers engaging said cams, links connecting the short arms of the first and second levers and the long arms of the second and tertiary levers, means on the last-named levers for transmitting power to a driven element, and weights on the short arms of the second levers counterbalancing them and said first levers.

In testimony whereof we affix our signatures in presence of two witnesses.

EDWARD F. MONTGOMERY.
REUBEN B. BURNHAM.
